UNITED STATES PATENT OFFICE

1,938,421

SPACER FOR ELECTRICAL WINDING COILS

Phillip A. Gilbert, Dalton, Mass., assignor to General Electric Company, a corporation of New York

Application March 23, 1932. Serial No. 600,659

2 Claims. (Cl. 175—356)

5 My invention relates to spacers for electrical winding coils such as are often used in transformers and reactors. A winding for electrical apparatus of this character is often in the form of a stack of annular or disk coils which are separated by radial spacing strips to provide spaces or ducts between the coils for the circulation of a cooling and insulating fluid such as air or specially prepared oil. The general object 10 of the present invention is to provide an improved coil spacer for disk coils.

Further objects and advantages of the invention will appear from the following description taken in connection with the accompanying 15 drawing in which Fig. 1 shows a transformer with disk coils separated by spacers constructed and arranged in accordance with the invention; Fig. 2 is a sectional view on the line 2—2 of Fig. 1; and Figs. 3, 4 and 5 are explanatory 20 perspective detail views of different forms of spacers constructed in accordance with the invention.

Like reference characters indicate similar 25 parts in the different figures of the drawing.

The transformer shown in Figs. 1 and 2 includes a magnetic core 10 with windings 11 and 12 formed of stacks of disk coils 13. These coils 13 are arranged in pairs, the two coils of each pair being separated from each other by an annular sheet 14 of insulating material. Adjacent 30 pairs of coils 13 are separated by radial spacers 15 which are spaced apart to provide ducts 16 through which a cooling and insulating fluid may flow to absorb and carry away heat from the coils 13.

The magnetic core 10 has two winding legs 17 which are surrounded by insulating cylinders 18. The two coil stacks formed by the coils 13 surround the cylinders 18, the inner edges of the 40 coils 13 being spaced from the cylinders 18 by spacing strips 19 extending parallel to the axis of the cylinders and interlocked with the inner ends of the radial spacers 15 to hold these radial spacers in place. An insulating and cooling fluid 45 in which the transformer may be immersed may thus flow between the inner edges of the coils 13 and the cylinder 18, as well as through the ducts 16 between those coils which are spaced apart by the radial spacers 15.

50 Each of the spacing strips 19 includes a channel 20 formed of fibrous insulating material such as pressboard, the longitudinal edges 21 of the channel being bent outwardly parallel to the plane of the base of the channel. The 55 radial spacers 15 are formed of flat strips 22 of

insulating material, any desired number of these strips being superposed if a single strip is not thick enough for the required spacing between the coils 13. The inner ends of the radial strips 22 are bifurcated to receive the spacing strips 19, the two spaced sides 23 of these bifurcated ends fitting against the sides of the channel 20 to prevent them from spreading. Notches 24 are provided at the bases of the inner edges of the sides 23 to engage the outwardly turned edges 21 of the strips 19 and thus lock the radial spacers 15 to the spacing strips 19. The spacing strips 19 also include fillers 25 in the channels 20 to hold the sides of the channels apart with their outwardly turned edges 21 securely engaged in the notches 24 of the radial spacer strips 22. The fillers 25 are shown in Figs. 3 and 4 as narrow strips of insulating material extending between the sides of the channel 20. In Fig. 5, the filler 25 is shown as a channel with its base across the open side of the channel 20. Other forms of filler may, of course, be used if desired. The channel 20 may be formed of a single thickness of insulating material, as shown in Figs. 3 and 5, or of more than one thickness, as shown in Fig. 4. The radial strips 22 are easily assembled on the strips 19 by slipping the inner bifurcated ends of the strips 22 onto the strips 19 from one end with the outwardly turned edges 21 of the channels 20 in 85 the notches 24 of the strips 22.

The invention provides a simple and securely interlocked coil spacer construction and one which is inexpensive because it may be formed entirely by inexpensive sheet material such as 90 common pressboard.

The invention has been explained by describing and illustrating several forms thereof, but it will be obvious that changes may be made without departing from the spirit of the invention and the scope of the appended claims. 95

What I claim as new and desire to secure by Letters Patent of the United States is:

1. The combination with a spacer to extend radially between spaced disk coils of an electrical winding, said spacer having a bifurcated end, of a channel formed of fibrous sheet material and extending through the bifurcated end of said spacer, the two sides of the bifurcated end of said spacer fitting against the sides of said channel and having notches in their inner edges, and the longitudinal edges of said fibrous channel being bent outwardly into said notches. 105

2. The combination with a spacer to extend radially between spaced disk coils of an elec- 110

trical winding, said spacer having a bifurcated end, of a channel formed of fibrous sheet material and extending through the bifurcated end of said spacer, the two sides of the bifurcated end of said spacer fitting against the sides of said channel and having notches in their inner

edges, and the longitudinal edges of said fibrous channel being bent outwardly into said notches, and filling means in said channel to hold its sides apart.
